MAGAZINE FOR SHUTTLE CHANGING
LOOMS

Lewis S. Vose, Worcester, Mass., assignor to
Crompton & Knowles Loom Works, Worcester,
Mass., a corporation of Massachusetts

Original application April 4, 1932, Serial No.
603,051. Divided and this application May 24,
1933, Serial No. 672,668

4 Claims. (Cl. 139—232)

This is a division of my application Serial No. 603,051.

The present invention relates to shuttle changing looms operating with shifting shuttle boxes and it is the general object of the invention to provide an improved magazine for the reserve shuttles.

It is another object of my invention to provide a multi-cell magazine built up of a plurality of substantially similar reserve shuttle units which can conveniently be arranged in parallel order to deliver shuttles to a carrier the path of which is common to the units. In this way I am enabled to increase the color capacity of the loom merely by adding additional units and increasing the length of travel of the carrier.

In this connection it is a further object of the invention to provide each unit with a selector mounted on a part of the shuttle unit and arrange the magazine so that escapement devices can be located between the units.

It is a still further object of my invention to provide simple and efficient means to control the trailing weft ends of the reserve shuttles. The several units or stacks are so arranged that the weft ends can be led to a thread holder located to permit free movement of the shuttles of any stack without disturbing the weft ends of any other stack. The thread slots of the several stacks are positioned to accommodate threads extending from the shuttle delivery eyes which may be located as in non-automatic looms, that is, with the shuttle eyes pointing toward the selvage when the shuttles are on the drop box end of the loom. This relation requires the shuttle eyes to be at the outer end of the shuttles when the latter are at the magazine end of the loom, and this ability to operate the automatic box loom with the shuttle eye located as on the non-automatic loom is a novel and efficient feature of my invention.

With these and other objects in view which will appear as the description proceeds, my invention resides in the combination and arrangement of parts hereinafter described and set forth in the claims.

In the accompanying drawings, wherein a convenient embodiment of my invention is set forth, Fig. 1 is a top plan view of the lay end and magazine made according to my present invention.

Fig. 2 is a detailed vertical section on an enlarged scale on line 2—2 of Fig. 1.

Fig. 3 is an enlarged detailed view of the lower

right outer end of the magazine looking in the direction of arrow 3, Fig. 1, and

Figs. 4 and 5 are detailed horizontal sections on reduced scale taken on lines 4—4 and 5—5, respectively, of Fig. 3.

Referring to the drawings, I have shown a breast beam 1, loom frame 2, and lay 3. Shifting shuttle boxes on the opposite side of the loom, not shown, are arranged to bring any one of a plurality of shuttles into action. A filling feeler mechanism, not shown, acts to stop the loom upon deficiency of filling, and start replenishment.

As shown in application Serial No. 603,051 there is provided a shuttle conveyor 77 with two rear fingers 78. A section 79 on the conveyor projects above and substantially at right angles to the fingers to form a shelf and back wall to support the fresh shuttle when it is transferred to the lay. After this shuttle has been placed on the lay the conveyor 77 is withdrawn forwardly by the conveyor lever and weaving is resumed.

The magazine forming the subject matter of this invention employs a plurality of shuttle storing and releasing units, one for each shifting shuttle box. There are shown two magazines 90 and 91 each made of three sections. A front inner section 92 of intermediate length and a short outer section 93 are both fixed upon the third rear long section 94 by bolts 95, see Fig. 1. The third section is bolted to the inner and outer magazine end frames 96 and 97, respectively, and have angular flanges 98 for the purpose. Thus, each long section supports two other sections and also serves to space and tie together the end walls or frames of the magazine.

The front sections of each magazine have their adjacent vertical edges spaced to define a thread slot 99, and the weft ends W and W' of the front and back reserve shuttles S and S', respectively, are led through their slots to a common thread holder 100 mounted on the inner frame 96. The delivery eyes D of the shuttles are preferably located adjacent to or in alignment with the thread slots, so that vibration of the reserve shuttles will not abrade the yarns. The rear section 94 of the front unit, being continuous between the end frames, defines a passageway for the wefts W', thus preventing them from becoming entangled with the front shuttles or their wefts.

The inner magazine frame 96 is mounted on the end of the breast beam, while the outer frame is suitably supported from the floor, and tie rods 102 help to hold the end frames in rigid and properly spaced relation.

Selector mechanism is employed to cause shuttle delivery to take place from the unit corresponding to the depleted weaving shuttle. Accordingly, each unit has a rock shaft 103 with 5 control fingers 104 fastened thereto, see Fig. 2. The rockshafts are mounted in lugs 105 on the rearward sections 94 of the magazines, two fingers being used on each rockshaft. The fingers of each rockshaft are movable under the corresponding magazine to prevent delivery of the 10 bottom shuttle.

The fingers are so moved that delivery can take place from but one unit at a time, namely, the one corresponding to the weaving shuttle to be 15 ejected. This control is exercised by the box motion not shown, by means of a rod 112 which is reciprocated vertically by the shifting of the shuttle boxes, and is pivoted to an arm 113 fixed on the rear shaft 103, see Fig. 3. This last 20 named shaft carries an arm 114 having a pin and slot connection with a similar arm 115 on the front shaft 103.

Thus the shafts 103 are given equal but opposite angular movements each time the boxes shift 25 and the delivery in turn is synchronously shifted from one unit to the other. By reason of the slotted connections shown, the proper amount of motion for the fingers 104 can be derived from the box motion. Each unit or shuttle cell 30 is seen, therefore, to have its own rock shaft 103 and selecting fingers.

Escapement devices are provided for each magazine to release the bottom shuttle and thereby permit selection by the fingers 104. These 35 escapement devices also act to prevent escape of more than one shuttle at a time from the selected unit. One such device is located at each end of each unit, and each escapement comprises a short vertical rock-shaft 116 journaled in bearing 117 40 on brackets 118 secured to an end frame 96. Each shaft 116 has a shoulder seating on top of its bearing and has secured thereto a long lower arm 119 and a short upper arm 120 above the bearing. The arms are adjustable along their 45 shafts to accommodate shuttles of varying heights, and angularly with respect to each other to adjust the time of escape of the shuttles.

The arms are so proportioned that when the 50 end of the long arm 119 is normally under a shuttle to support a whole stack of shuttles the short arm will swing out of the path of descending shuttles, as shown in magazine 90, Fig. 4, but when the shafts 116 rock, the lower arm moves to release the bottom shuttle as shown at magazine 91, same figure. The lowest shuttle is thereby released so that it will be free to drop from the magazine. The short arms act to prevent descent of the shuttles above the bottom one which has thus been delivered. As the arms 55 return to their normal position, the shuttle resting on the upper arms drops to the lower arms ready for the next operation. These escapement devices, as stated, are located one at each end of each unit and the arms of any pair are 60 operated simultaneously, hence the shuttles are lowered in perfectly horizontal relation.

In order to transport a released shuttle to the 65 previously described conveyor, I provide a carrier 121, see Fig. 5, having at each end a supporting portion 122. Each of said portions slides freely in a slot or track 123, Figs. 2 and 3 formed on each magazine end frame. The tracks are inclined downwardly and rearwardly so that the 70 path of the carrier will intercept the arc of travel

of the conveyor 77. By this arrangement there will be rapid divergence of the respective paths of the carrier and conveyor, permitting the latter to pass the carrier and assume a position nearer the front of the loom, from which position the conveyor moves rearwardly to take the shuttle from the carrier. The carrier is common to all the magazines, the tracks being long enough to permit the necessary travel of the carrier.

From the foregoing it will be seen that I have provided a multicolor magazine built up of a plurality of similar units each of which supplies a distinctive kind of shuttle. It will also be seen that each unit serves to space and brace the end plates of the magazine, and that the rear section of a forward unit serves as a guard for the weft ends of the unit behind it. Furthermore, the front sections of each unit are so formed as to define a slot which is in alignment with the delivery eyes of the shuttles, and these slots and the eyes are placed so that the shuttle can operate in the normal manner found in non-automatic box looms, that is, with the delivery eyes pointing toward the selvage when the shuttles are in the shifting shuttle boxes. Each unit carries its own selector, while the escapement devices therefore are carried by the magazine frames which are held in spaced relation by the units so that said escapement devices are properly related to the stored shuttles.

Having thus described my invention it will be seen that changes and modifications may be made therein by those skilled in the art without departing from the spirit and scope of the invention and I do not wish to be limited to the details 105 herein disclosed, but what I claim is:

1. In a multicolor shuttle changing loom, a pair of spaced end magazine forming plates, and a plurality of similar reserve shuttle magazine cells located between said plates, each cell being formed 115 of a single member extending between the plates and two other members spaced from each other to define a thread slot and fixed with respect to the single member.

2. In a multicolor magazine for shuttle changing looms, a pair of spaced magazine forming end frames, a plurality of shuttle storing units between the frames, each unit including a rear section connected to and spacing both end plates, and each unit including a pair of front sections having their adjacent ends spaced to define a thread slot for the weft ends of the stored shuttles.

3. In a multicolor magazine for shuttle changing looms, a pair of spaced magazine forming end frames, a plurality of shuttle storing units 130 between the frames, each unit including a rear section connected to and spacing both end plates, each unit including a pair of front sections having their adjacent ends spaced to define a thread slot for the weft ends of the stored shuttles, and 135 a thread holder in front of the forward unit, the weft ends of the shuttles in any unit extending over the rear section of the unit in front thereof to the thread holder.

4. In a reserve shuttle magazine for shuttle changing looms, a plurality of units each to contain a supply of reserve shuttles the thread delivery eyes of which point away from the selvage of the cloth being woven, a pair of front sections for each unit spaced to define a thread slot which is in substantial alignment with the delivery eyes of the shuttle, and a thread holder for the thread ends in front of said slot.

LEWIS S. VOSE.
